UNITED STATES PATENT OFFICE.

HARRY J. HUFFORD, OF SCRANTON, PENNSYLVANIA.

THREAD CLEANER.

Application filed May 13, 1927. Serial No. 191,149.

The invention relates to improvements in thread cleaners designed primarily for use upon spinning, doubling and analogous machines, and the object of the invention is 5 to provide a new and improved form of cleaner which may be readily adjusted for use with threads of different sizes.

With the foregoing and other objects in view, the invention resides in the novel subject matter hereinafter described and claimed, the description being supplemented by the accompanying drawing.

Fig. 1 is a side elevation of a cleaner constructed in accordance with my invention.

Figs. 2 and 3 are transverse sectional views on the correspondingly numbered lines of Fig. 1.

Fig. 4 is a horizontal section on line 4—4 of Fig. 1.

Fig. 5 is a disassembled perspective view.

Fig. 6 is a horizontal sectional view on the plane of the key-controlled set screw for clamping the scraping blades in adjusted position.

In the drawings above briefly described, the preferred form of construction has been illustrated, and while this construction will be hereinafter specifically described, it is to be understood that within the scope of the invention as claimed, variations may be made.

In the drawing above briefly described, the numeral 7 designates an appropriate base to which a fixed scraping knife 8 is secured in any desired manner. Preferably, the upper side of the plate 7 is provided with upstanding parallel flanges 9 between which the lower end of the blade 8 is snugly received, said blade end being secured between said flanges by any desired fastening means, such as the screw 10. When such a screw is used, its removal permits the substitution of a new blade for one which has become worn.

A flat vertical sleeve 11 slidably surrounds 45 the blade 8 and has flared, thread receiving throats 12 formed in its opposite sides, the inner ends of these throats being preferably enlarged somewhat as seen at 13. The thread scraping edge 14 of the fixed blade 50 8 is disposed at one side of the throats 12, and a thread scraping edge 14^a of a movable blade 8^a, is disposed at the opposite side of said throats. This blade 8^a is rigidly secured in the sleeve 11 and contacts snugly 55 with opposed flat sides and with one edge of the latter. Preferably, a screw 10^a is

employed to secure the blade 8^a in the sleeve 11 and when this screw is removed, the blade may be removed to permit the insertion of a new one.

The opposed edges 14—14^a of the two thread scraping blades are oblique to the length of the sleeve 11, so that by shifting this slide and the movable blade 8^a carried thereby, upwardly or downwardly upon the blade 8, said edges may be brought toward or away from each other to set the device for use upon thread of any diameter within limits. To then lock the blade 8 and the sleeve 11 against relative movement, 60 suitable means is employed, preferably in the form of a key-controlled set screw 15 threaded into a boss 16 in the sleeve 11, in position to tightly contact with the blade 8. By having the set screw 15 of key-controlled nature, it is tamper-proof. Hence, after the device is once set, its setting cannot be disturbed by unauthorized persons, such as the machine attendants. When initially setting the device, a gauge of proper thickness is inserted between the edges 14—14^a and the sleeve 11 is slid upon the stationary blade 8 until both of said edges contact tightly with said gauge. Then by use of the key, the set screw 15 is tightened, thus 65 securely holding the edges 14—14^a in correctly spaced relation.

The thread is guided between the scraping edges 14—14^a by suitable guides (not shown) disposed at opposite sides of the device, and said blades serve to effectively remove any enlargements which would cause trouble if permitted to pass. Whenever any of the material scraped from the thread, so accumulates between the edges 14—14^a, as to 70 interfere with operation of the cleaner, a gauge or the like may be used to force such accumulated material toward the inner ends of the throats 12. At these points, the edges 14—14^a are formed with opposed notches 14', providing ample space through 75 which the inwardly forced material may be removed.

While any desired locking means may be provided for the set screw 15, I prefer the 80 construction shown in Fig. 6, wherein the screw has a cylindrical bore 17 to receive the key 18. The screw 15 has at its inner end a longitudinal notch 19 and the key has pivoted at 20 in a notch in its cylindrical end, 85 an elongated dog or detent 21 which enters the notch 19 to lock the key 18 and screw 15 90

to turn together. When the key is inserted in the bore 17, the dog is in longitudinal alinement with the key but when the dog strikes the blade or knife 8 and the key is rotated, the dog swings on its pivot 20 and its free end enters the notch 19 to cause the set screw to rotate with the key. The shape and mounting of the dog is such that it can swing only through an arc of about ninety degrees as will be seen on referring to Fig. 6. As the key is withdrawn from the screw its dog swings back into horizontal alinement with the key. It will therefore be seen that no one without a key can change the adjustment of the device.

On account of the existing advantages for the details disclosed, they are preferably followed. However, within the scope of the invention as claimed, variations may be made as above stated.

I claim:-

1. A thread cleaner comprising a blade and means for fixedly securing the same to a support, a sleeve slidably surrounding said blade and having thread-receiving throats in its opposite sides, said blade having a thread scraping edge disposed at one side of said throats, a second thread scraping blade having a scraping edge disposed at 30 the opposite side of said throats, the two scraping edges being oblique to the length of the sleeve, and means for securing said sleeve to said first named blade after relative sliding thereof to dispose said scraping edges 35 the desired distance apart.

2. A thread cleaner comprising a base plate having spaced parallel flanges, a blade having one end secured between said flanges, a sleeve slidably surrounding said blade and having thread-receiving throats in its opposed sides, said blade having a thread scraping edge disposed at one side of said throats, an additional blade secured in said sleeve and having a thread scraping edge disposed at the opposite side of said throats, 45 the two thread scraping edges being oblique to the length of the length of the sleeve, and means for securing said sleeve and the first named blade together after relative sliding thereof to set said thread scraping edges the 50 desired distance apart.

3. A thread cleaner comprising a blade and means for fixedly securing it to a support, a sleeve slidably surrounding said blade and having thread-receiving throats in 55 its opposed sides, said blade having a thread scraping edge disposed at one side of said throats, a second blade snugly received between said opposed sides of said sleeve and having a thread scraping edge opposed to 60 the aforesaid scraping edge, these two edges being disposed oblique to the length of the sleeve, means detachably securing the second blade in the sleeve, and means for securing said sleeve to the first named blade after 65 relative sliding thereof to space the scraping edges the desired distance apart.

In testimony whereof I have hereunto affixed my signature.

HARRY J. HUFFORD.
